ASSIGNORS TO THE O & J MACHINE COMPANY, OF WORCESTER, MASSACHUSETTS, A
CORPORATION OF MASSACHUSETTS

LABEL WIPING DEVICE

Application filed August 17, 1928. Serial No. 300,258.

This invention relates to means for wiping down the edges of labels on a bottle or other package.

The principal objects of the invention are to provide a construction capable of use on small and large bottles and with small and large labels without adjustment and to avoid the condition that exists with the long brush used for this purpose, namely, that after the first tufts of bristles have passed over the label the bottle or package itself engages those following and holds them out of the way of the label so that they do not engage its edge. This is done according to the present invention by dividing up the brush and thus having forward tufts of bristles come into contact with the labels several times during the passage of the article and label through the wiping device.

Another object of the invention is to provide means for holding the rear bristles against the forward ones so as to make the bristle structure stiffer and more unitary.

Other objects and advantages of the invention will appear hereinafter.

Reference is to be had to the accompanying drawings in which

Fig. 1 is a plan of a part of a labeling machine with a wiping device constructed in accordance with this invention;

Fig. 2 is a front elevation of the same, and

Fig. 3 is a rear end view of one of the bristle holders.

When an article like a bottle with a label on the front is passed along a fixed brush the front bristles engage the label and tend to brush it down at the edge and almost immediately the bottle or article to be labeled will come into engagement with the bristles at a distance from their free ends and hold them back away from the label if the label covers only a small area on the bottle. For that reason, the brush, except the forward end, is almost useless. It is for the purpose of avoiding this difficulty and providing for effectively brushing down the edges of the label that this invention is designed.

The invention is shown as applied to a labeling machine in which the article 10 to be labeled passes through a course between

two opposite holders 11 in which the brushes are mounted. Instead of employing a single brush on each side the brushing device is made in the form of a plurality of small brushes, each comprising a back 12. These backs are separated from each other a short distance so that they have all the effect of a single brush extending throughout the same distance and also an improved effect as will appear.

Each of these brush backs 12 is mounted on a bell crank 13 pivoted on a stud 14 and held in position for engaging the label by a spring 16. The bell crank is provided with an adjustable screw 17 abutting against the support 11 which carries the brushes to limit the backward movement of the brush backs and thus define their normal position. The brushes are placed near together and they will operate effectively on both small and large bottles.

Each of the brush backs is provided with a series of tufts 18 of bristles constituting a brush. For the purpose of stiffening the forward bristles which come into contact with the article to be labeled a wire 20 is secured to the back of each bristle back and extends around the front edge and is bent into the form of an inclined loop on the rear which engages the rear tufts of bristles and is so proportioned as to bend them forward as indicated in Fig. 1. This brings the rear row of tufts into contact with the next row thus, so to speak, uniting these two rows into one and making them stiffer without any of them engaging the articles to be labeled and they will exercise more force to prevent the front row of bristle tufts from yielding too much, thus forcing the edge of the label down.

Furthermore it will be seen that this brings all the bristles of this brush near enough together so that they will not any of them be held out of the way of the label by the bottle 10 as it passes through. The principal advantage, however, is that after the bottle has passed through one of the brushes, or a pair of them on opposite sides as shown, the bottle will then pass through a space free of bristles and will come to

another set, the forward ones of which will engage the label and wipe over every portion of it so as to effectively wipe down its edges. The action of the bristles is shown at the center of Fig. 1 where the bottle is just coming into contact with them. It will be seen that the front bristles are yieldingly held forward by the rear bristles and pressure applied to them. The position of the rear bristles is limited by the wire loops 20 so that the full force can be used in wiping down the label.

This arrangement can be employed efficiently to wipe down either small or large labels on either small or large bottles without adjustment. This avoids the usual loss of time in adjusting the brushes and trying the machine out with different adjustments, sometimes over and over. By making the 20 brushes in sections in this way, the brushes can be set close together and will work under the different conditions mentioned.

Although we have illustrated and described only one form of the invention we 25 are aware of the fact that modifications can be made therein by any person skilled in the art without departing from the scope of the invention as expressed in the claims. Therefore we do not wish to be limited in 30 this respect but what we do claim is:—

1. As an article of manufacture, a label wiping brush comprising a back with rows of bristles projecting from the front thereof and a wire loop extending at an angle 35 from the front edge of the back to engage the rear bristles at an intermediate point between their ends and hold them forward, the ends of said loop extending around on the back and held thereto.

2. As an article of manufacture, a label 40 wiping brush comprising a back with rows of tufts of bristles projecting from the surface thereof and normally set in the back in separated relationship, and means extending 45 from one edge of the back to a point adjacent to the other edge for engaging the bristles at said other edge at a point substantially half way between their ends and compressing the first row of tufts against the other rows so that the tufts are all in 50 contact along the active face of the brush.

In testimony whereof we have hereunto affixed our signatures.

CHARLES H. OSLUND.

JOHN EMANUEL JOHNSON.
